DEFECATOR WITH INTEGRAL EVACUATOR

William C. Groeniger, Columbus, Ohio, assignor
to John B. Pierce Foundation, New York, N. Y.,
a corporation of New York

Application June 7, 1935, Serial No. 25,475

4 Claims. (Cl. 4—69)

My invention relates to defecators comprising a bowl proper and an evacuator integral therewith.

Preferred forms of my invention embody jet means for imparting a vertical movement to the contents, i. e. afterfill effluent and contained matter, combined with jet means for effecting an upward movement of the contents upwardly through the upflow half-leg and thence into the downflow half-leg, i. e. evacuator, to be eventually discharged, as into a soil or other waste pipe.

Most preferred forms of my invention embody the principles of the defecator proper set forth and claimed in my copending application Ser. 15 #749,069, filed October 19, 1934, entitled Defecators and the general principles of my evacuator, i. e. downflow half-leg set forth in my copending application Ser. #4,620, filed Feb. 2, 1935, entitled Evacuators. In such preferred forms of my invention, the eventual discharge is through an outlet disposed laterally relative to the bowl.

Pursuant to my present invention, the downflow half-leg, i. e. evacuator, as well as the upflow half-leg are constructed integrally with the bowl proper and additionally such downflow half-leg and such upflow half-leg are arranged in major portion anteriorly of the rear face of the thus combined bowl proper and upflow and downflow siphon-legs.

Further features and objects of the invention will be more fully understood from the following detail description and the accompanying drawings, in which

Fig. 1 is a central vertical section of one preferred form of my invention;

Fig. 2 is a top plan view of Fig. 1;

Fig. 3 is a vertical sectional view on line 3—3 of Fig. 1, and transversely of the plane of the section of Fig. 1;

Fig. 4 is a detail sectional view on line 4—4 of Fig. 1;

Fig. 5 is a detail sectional view on line 5—5 of Fig. 1.

Fig. 6 is a detail sectional view on line 6—6 of Fig. 1.

Referring to the drawings, the bowl proper 10 may be of any desired outer and inner contours and configurations suitable for carrying out the purposes of my invention. As illustrated, and as preferred, the bowl proper comprises a rear face portion 11, desirably uniplanar and adapted to abut a vertically extending wall or equivalent of a building or other structure, suitable provision being made for supporting the combined bowl structure in such position.

Preferred forms of the bowl proper of my invention, and as shown in the drawings, comprise a main water channel 12 communicating with the rim channel 13 which extends in opposing directions at and about the top 14 of the bowl proper, merging at the front 15 of the bowl proper in the downwardly extending channel 16 communicating with the main jet 17, preferably directed toward the center 18a of the well 18 of the bowl proper and in substantial alignment with the upflow leg 19. The downwardly extending inner wall portion 20 of the bowl proper terminates preferably, see 21, at a location anteriorly of the center 18a of the well 18, such center being desirably the lowermost point of the interior of the bowl. The wall portion 22 defining the lower wall of the upflow leg 19 terminates at its top, see 23, at a suitable height to determine the normal level 24 of the effluent 25.

A suitable form of vortex-effecting jet is had by the provision of a channel 26 communicating at its upper port with the main water channel 12 and leading to the jet opening 27, located below the normal level 24 of the effluent and directed to impart a clockwise or counter-clockwise, as preferred, movement to the effluent 25 and contained matter.

Rim openings 28 of suitable form and direction are provided in the lower face of the top i. e., rim portion 14 of the bowl proper, the effective direction or directions of such rim opening 28 being in correspondence to the direction of vertical movement imparted by the vortex jet 27. As is indicated in the drawings, the direction of vertical movement imparted by the jet 27 and conjointly by the rim jets 28 is in counter-clockwise direction as viewed from the top of the bowl proper, indicated by the arrow 30 in Fig. 2.

The downflow half-leg 31 is defined by the lower face of the wall portion 22 and the inner face of the wall portion 32 and communicates with or is integral with, as shown, the discharge passage 33, the port 34 of which communicates with the soil line, as per a Y-or other suitable fitting, or otherwise suitably discharged.

Such discharge port 34 is formed in the rear face 11 of the combined bowl structure. Preferably in alignment with the defining wall of the discharge port 34 is the defining wall of the inflow port 35 leading to the main water channel 12, the above enumerated essential parts being disposed anteriorly of the rear face 11 of the combined bowl structure, and also preferably integrally with one another.

Embodiments of my invention may be molded

of porcelain or other suitable vitreous material, or may be made of metal cast to the desired outer and inner contours and configurations and providing for the above stated essential channels and 5 their ports and other parts, and may be suitably coated with enamel or other finish, or equivalent, as is readily understood by those skilled in the art.

Suitable means are provided for the unitary 10 support of the combined bowl structure. Such supporting means is preferably carried out independently of the connections at the inflow port 35 with the piping for the supply of water or other effluent to the main water channel 12 and also 15 independently of the connection at the discharge port 34 of the discharge channel 33 for communication with the soil or other waste piping. As 20 one form of such preferred means of support of embodiments of my invention, I illustrate in the drawings, see Fig. 3 in particular, the perforations 36 formed in the rear and vertically extending ledge 37, for receiving bolts or equivalent, for affording securement to and support, as by the 25 studs of a partition or to the wall material, or equivalent, thus effecting a suspension of the bowl and its above stated appurtenant parts independently of all piping connections leading to and from the efficator.

Pursuant to the present invention, the upflow 30 and downflow legs constituting the complete siphon, are structurally integrally incorporated in the completed bowl structure. To such end, the upper terminus 23 of the wall 22 disposed between and defining the upflow and downflow half-siphon legs is of reduced horizontal dimension, 35 see Fig. 1, comparable to an edge formation, and preferably flattened to extend in a substantially horizontal plane, as indicated in Fig. 6; also, the head, i. e., elbow section 40 of the thus completed siphon formation is located anteriorly of the axis of the downflow leg 31, as compared with the evacuator set forth in my aforesaid application Serial #4,620. Also, the downflow leg 31 is 40 arranged anteriorly of the rear wall of the completed bowl structure, and with its axis to form an angle to the horizontal, and preferably lies substantially in the vertical, thereby, further, disposing the foot portion 42 of the downflow leg anteriorly of the rear wall of the combined bowl 45 structure, and preferably having its axis of discharge disposed substantially at right angles to the plane of the rear wall 11 of the combined bowl structure.

The general characteristics of the upflow leg 50 19 are substantially as is set forth in my aforesaid application Serial #749,069. The general principles of the downflow leg 31 in my present invention, are substantially those set forth in my aforesaid application Serial No. 4,620, including 55 inter alia as an essential, the embodiment of suitable means for positively precluding the inflow of air upwardly of the evacuator, i. e., in direction reversely of the direction of flow of the effluent, and accordingly preserving the vacuum within 60 the evacuator during the stage of its discharge.

As illustrated in the drawings, such vacuum preserving means comprises a channel section, 65 see 31a, having a cross-sectional area appreciably less than the cross-sectional area of the upflow leg 19 or the mean cross-sectional area thereof. Such vacuum preserving means, as shown further 70 comprises effluent-curtain-forming means, effected by the structure of the wall formation 41, preferably arcuately toward and to the vertical, relative to the axis of the downflow leg 31, and en-

gendering a curtain formation of and by effluent in its downward flow, such curtain formation being enhanced by the depressed horizontal wall formation of the foot-portion 42.

The depressed wall formation 42 functions as 5 a pool for the collection of successive portions of the effluent at a mean level at or substantially passing horizontally through the point indicated at 42a, thus effectually reducing the cross-sectional area of the channel at the location indicated by the section line 5—5, see Fig. 1.

Cooperating with such curtain-forming wall formation 41 the wall formation 43 of the lower portion of the wall 22 is formed arcuately, whereby coupled with the reduced cross-sectional area 15 of the channel section 31a above referred to, the effluent is positively fashioned into a curtain formation and at substantially the beginning of the stage of siphonic discharge of the effluent through the efficator, i. e., siphon passageway. 20

From the above, and as appears more fully from the disclosures of my aforesaid copending applications, Serial #749,069, filed October 19th, 1934, entitled Defecators, Serial #733,259, filed June 30th, 1934, entitled Lateral outlet defecator 25 and Serial #4,620, filed February 2nd, 1935, entitled Evacuators, upon release of flow of the effluent from a flush tank or equivalent, or from a pressure piping as per a flush valve or equivalent, the effluent enters the main water channel 30 12, thence into and through the rim channel 13 and into and through the vortex channel 26, the latter giving rise upon formation of the jet through the jet opening 27 to a vertical movement of the afterfill and contained matter, within 35 the interior of the bowl proper, the former giving rise to the formation of the main jet through the jet opening 17, whereby the afterfill and supplied effluent flow upwardly within and through the upflow leg 19, thence over the dam 23, thence into 40 and downwardly of the downflow leg 31, relative retardation of the flow of the effluent in the downflow leg 31 ensuing by the action of the relatively reduced cross-sectional channel section 31a, causing inter alia the rise of the effluent at and above 45 the dam 23 within and to a substantial extent of the head or elbow section 40, whereby upon continued supply of the effluent to and through the stated jet openings and consequent continued flow of the effluent into the evacuator 31, the air 50 of the elbow section 40—normally under atmospheric pressure—is entrained more and more by and with the effluent, until the desired partial vacuum, i. e., subatmosphere pressure of the stated air retained elbow section 40 is attained, at 55 which stage the full siphonic action takes place. Concomitant with the effectual flow of the effluent to and through the reduced cross-sectional channel section 31a, a curtain is formed by the successive portions of the effluent, primarily by 60 the wall formation 41, enhanced by the arcuate wall formation 43 and further by the depressed pool-forming wall section 42, such curtain effectually precluding the flow of air into and/or through the evacuator and preserving the sub-atmospheric, i. e. vacuum, pressure of the stated retained air within the head or elbow section 65 of the evacuator.

Simultaneous and cooperative with the flow of effluent through the vortex jet 27, effluent is supplied from the rim channel 13 to and through the rim openings 28, in like vertical-effecting directions, serving primarily to scour the upper vertical faces of the bowl proper, as will be understood.

Upon completion of the discharge of the matter-containing portion of the effluent, originally the afterfill, and cessation of the supply of additional effluent, the siphonic action is gradually brought to conclusion, namely by air entering the lower, i. e. entry opening of the upflow leg 19 and merging with the air within the head or elbow section 40, previously under subatmospheric pressure, and restoring the same to normal i. e., atmospheric pressure, the afterfill of the effluent being afforded by the last stages of supply of the effluent through the vortex jet 27, the main jet 17, and through the rim openings 28.

Whereas I have illustrated my invention as incorporated in specific types of bowl constructions, it is understood that my invention is applicable to all suitable types of sanitary devices employing or adapted to employ the siphonic principle in the discharge of the same.

20 I claim:

1. As a new article of manufacture, a sanitary device comprising a bowl proper provided with jet discharging means, channel means adapted for siphonic action upon the effective supply of effluent to and through said jet discharging means, said channel means comprising a downwardly directed channel portion, said channel means including a downflow effective section of re-entrant formation including a cross-sectional area appreciably less than the mean cross-sectional area of anterior sections of said channel means, said down flow section including a lowerly disposed horizontally extending foot portion and a thereto relatively upwardly disposed portion having an edge formation, effecting with such foot portion a vertical curtain of the effluent, said bowl proper and said channel means being formed of unitary integral material, the discharge opening of said channel means extending horizontally and disposed within the over-all horizontal dimensions of the upper face of the article.

2. As a new article of manufacture, a sanitary device comprising a bowl proper provided with jet discharging means, channel means adapted for siphonic action upon the effective supply of effluent to and through said jet discharging means, said channel means comprising a downwardly directed channel portion, said channel means including a downflow effective section of re-entrant formation including a cross-sectional area appreciably less than the mean cross-sectional area of anterior sections of said channel means, said down flow section including a lowerly disposed horizontally extending foot portion and a thereto relatively upwardly disposed portion having an edge formation, effecting with such foot portion a vertical curtain of the effluent, said channel means further including a discharging section directed in its axis along the horizontal, said bowl proper and said channel means being formed of unitary integral material, the dis-

charge opening of said channel means extending horizontally and disposed within the over-all horizontal dimensions of the upper face of the article.

3. As a new article of manufacture, a sanitary device comprising a bowl proper provided with jet discharging means, channel means adapted for siphonic action upon the effective supply of effluent to and through said jet discharging means, said channel means comprising a horizontally extending discharge section and further comprising a wall formation disposed anteriorly of said discharge section and providing for downward flow of the effluent, said discharge section including a lowerly disposed horizontally extending foot portion, said channel means further comprising an arcuate wall portion extending generally vertically downwardly and terminating in an edge formation disposed upwardly relative to said horizontally extending foot portion, said edge formation and said horizontally extending foot portion effecting the formation of a curtain by and of the effluent therebetween, said bowl proper and said channel means being formed of unitary integral material, the discharge opening of said channel means extending horizontally and disposed within the over-all horizontal dimensions of the upper face of the article.

4. As a new article of manufacture, a sanitary device comprising a bowl proper provided with jet discharging means, channel means adapted for siphonic action upon the effective supply of effluent to and through said jet discharging means, said channel means comprising a horizontally extending discharge section and further comprising a wall formation disposed anteriorly of said discharge section and providing for downward flow of the effluent, said discharge section including a lowerly disposed horizontally extending dished foot portion, said channel means further comprising an arcuate wall portion extending generally vertically downwardly and terminating in an edge formation disposed upwardly relative to said horizontally extending dished foot portion, said edge formation and said horizontally extending dished foot portion effecting the formation of a curtain by and of the effluent, said channel means further comprising a downwardly directed channel portion, said channel means including a downflow effective section having a cross-sectional area appreciably less than the mean cross-sectional area of anterior sections of said channel means, said bowl proper and said channel means formed of unitary integral material, the discharge opening of said channel means extending horizontally and disposed within the over-all horizontal dimensions of the upper face of the article.

WILLIAM C. GROENIGER. 60
